* cited by examiner

Primary Examiner—Charles A. Rademaker*Assistant Examiner*—Carla Jobe Wright(74) *Attorney, Agent, or Firm*—Brij K. Agarwal; Eckert Seamans Cherin & Mellot, LLC(57) **CLAIM**

The ornamental design for a handset, as shown and described.

DESCRIPTION

FIG. 1 is a perspective view of a handset depicting our new design;
FIG. 2 is another perspective view thereof;
FIG. 3 is a left side elevational view thereof;
FIG. 4 is a front elevational view thereof;
FIG. 5 is a bottom plan view thereof;
FIG. 6 is a top plan view thereof;
FIG. 7 is a right side elevational view thereof; and,
FIG. 8 is a rear elevational view thereof.

The broken line showing of the rectangular feature on the rear of the handset in FIGS. 2, 6, and 8 is for illustrative purposes only and forms no part of the claimed design.
